UNITED STATES PATENT OFFICE.

THOMAS B. HOWE, OF SCRANTON, PENNSYLVANIA, ASSIGNOR OF TWO-
THIRDS TO G. A. CLEARWATER AND M. A. GOODWIN, OF SAME PLACE.

JAR-FASTENER.

SPECIFICATION forming part of Letters Patent No. 387,304, dated August 7, 1883.

Application filed December 30, 1887. Serial No. 259,388. (No model.)

To all whom it may concern:

Be it known that I, THOMAS B. HOWE, of Scranton, in the county of Lackawanna and State of Pennsylvania, have invented certain new and useful Improvements in Jar-Fasteners; and I do hereby declare the following to be a full, clear, and exact description of the same, reference being had to the accompanying drawings, forming a part of this specification, and to the figures and letters of reference marked thereon.

This invention relates to certain improvements in fasteners for fruit jars or bottles in which a bail passes over the top of the jar and has pivoted thereto a locking-lever for bearing on the top of the cover or stopper, its object being to improve the construction of the fastening, whereby the cost of manufacture is reduced and the efficiency and ease of manufacturing the fastening increased. To these ends the invention consists in certain details of construction and combinations and arrangements of parts, to be hereinafter described, and pointed out particularly in the claims at the end of this specification.

In the accompanying drawings, Figure 1 is a perspective view of a fastener constructed in accordance with my invention. Fig. 2 is a top plan view of the same, and Fig. 3 is a side elevation of the fastener closed. Figs. 4 and 5 are views of modifications.

Similar letters of reference in the several figures indicate the same parts.

The bail A, passing over the top of the jar, is pivoted in eyes formed in the neck-wire, as is usual in this class of fasteners, its central portion, B, being raised above the portions on either side in order to form shoulders or abutments C, for a purpose to be presently explained.

The locking-lever is formed of spring-wire somewhat after the manner of that shown in my prior patent, No. 370,394, dated September 27, 1887—that is to say, the wire is doubled in the center to form the handle D, then is carried back and formed into the large coils E, circling outward in opposite directions, as shown in Fig. 2, a bridge-piece or core, F, having the enlarged ends G, being confined within said coils only in the present instance.

The ends of the wire do not pass off to one

side of the jar, but are formed into eyes H close to the said coils, which eyes encircle the bail in the raised central portion. The handle D and eyes H are formed in such relative positions as that when both are in engagement with the jar-cover in locked position the said eyes will be slightly forward of the center of the coils, in which position the pull by the bail will tend to hold the handle down and the fastening locked.

The coils E, it will be noted, are of a diameter equal to or slightly greater than the distance between the bail and jar-cover, and the bail, being pivoted closely to the coils, will, when under pressure, rest on them and cause them to bear their proportion of the weight.

When the locking-lever is thrown into locked position, the tendency of the spring will be to flatten or spread, and the core or bridge-piece F is employed to counteract this tendency, the enlarged ends of the said piece effectually preventing the spreading or separating of the coils, and, by taking up the downward pressure, either by resting on the jar-top on the sides or else entirely filling said coils, counteracting the tendency to flatten. The eyes on the ends of the locking-lever are prevented from spreading by the shoulders or abutments C on the bail.

It is obvious that the construction herein-before described may be somewhat modified without departing from the spirit of my invention. For instance, the core or bridge-piece may be entirely omitted and the shoulders on the bail depended on to prevent the spreading of the coils of the locking-lever, and said shoulders or abutments may be in the form of eyes engaging those on the locking-lever, or enlargements on the bail may be employed, as shown in Figs. 4 and 5, although I prefer the construction first described.

Having thus described my invention, what I claim as new is—

1. In a jar-fastener, and in combination with the jar and its cover, a bail passing over said cover and a spring-wire locking-lever formed into eyes surrounding the bail and into large coils resting on the jar-cover at the bottom, said bail taking a bearing on the top of said coils, substantially as described.

2. In a jar-fastener, and in combination with

the jar and its cover, a bail passing over said cover, and a spring-wire locking-lever doubled at the center to form the handle, then formed into the outwardly-circling coils resting on said cover and affording a bearing for the bail, the ends of said wire being formed into eyes surrounding the bail, substantially as described.

3. The combination, with a jar, a bail passing over its cover, and a wire locking-lever

pivotedly connected to the bail and formed with large coils resting on the cover, of a core-piece passing through said coils, having enlarged ends for preventing the longitudinal expansion of said coils, and a handle for operating the lever, substantially as described.

THOMAS B. HOWE.
